UNITED STATES PATENT OFFICE.

OSCAR L. DANFORTH, OF SAN DIEGO, CALIFORNIA, ASSIGNOR TO MATILDA DANFORTH, OF SAN DIEGO, CALIFORNIA.

WINDOW-LOCK.

1,311,052.

Specification of Letters Patent. Patented July 22, 1919.

Application filed May 13, 1919. Serial No. 296,836.

To all whom it may concern:

Be it known that I, OSCAR L. DANFORTH, a citizen of the United States, residing at San Diego, in the county of San Diego and 5 State of California, have invented a certain new and useful Window-Lock, of which the following is a specification.

My invention relates to a window lock for locking the window sash in certain positions relatively to the window frame and the 10 objects of my invention are: first, to provide a window lock of this class in which the window sash may be readily locked in opened or closed position or in various intermediate positions as desired; second, to 15 provide a lock of this class which may be readily applied to the ordinary sash now in use; third, to provide a lock of this class which is in the form of an eccentric and 20 when in operative position prevents the sash from moving either up or down, as the further the sash is moved in either direction the tighter it engages the window frame and fourth, to provide a lock of this class which 25 is very simple and economical of construction, durable, easy to install, easy to operate and which will not readily deteriorate or get out of order.

With these and other objects in view as 30 will appear hereinafter, my invention consists of certain novel features of construction, combination and arrangement of parts and portions as will be hereinafter described in detail and particularly set forth in the 35 appended claims, reference being had to the accompanying drawings and to the characters of reference thereon which form a part of this application, in which:

Figure 1 is a side elevational view of a 40 fragmentary portion of a window frame and sash and showing my lock in inoperative position on the window sash; Fig. 2 is a similar view and showing the lock in operative position; Fig. 3 is a sectional view through 45 3-3 of Fig. 2 and Fig. 4 is a diagrammatic view of my lock showing its position by solid lines when the lock is just placed in operative position and showing by dotted lines the position it would take if the window sash 50 was forced downwardly.

Similar characters of reference refer to similar parts and portions throughout the several views of the drawings.

The screw 1, support 2, pivotal member 3, 55 engaging member 4, pin 5 and handle 6 con-

stitute the principal parts and portions of my window lock.

The support 2 is pivotally mounted on the window sash by means of the wood screw 1 the head of said screw being countersunk into the said support 2 and pivotally mounted on this support is the pivoted support 3 by means of a pin 5, the member 3 being bifurcated and the extended ends of said pin 5 secured therein. This member 3 is 60 semicircular in form and provided with two extended portions the one offset at 3^a and spaced apart from the other member to their outer edges. Mounted between these members and secured thereto is the member 4 65 which is composed of an elastic and adhesive material preferably rubber and the edge may be notched as shown in Figs. 1, 2 and 3 or smooth as shown in Fig. 4 as desired. This edge is adapted to engage the window 70 frame when the lock is folded into operative position as shown in Figs. 2, 3 and 4 of the drawings. This member 3 is provided on the one side with the handle member 6 which is for the purpose of facilitating the 75 folding movement of the members 3 and 4 into and out of engagement with the window frame.

Though I have shown and described a 80 particular construction, combination and arrangement of parts and portions I do not wish to be limited to this particular construction, combination and arrangement but desire to include in the purview of my invention the construction, combination and arrangement substantially as set forth in the 85 appended claims.

It is obvious that with this construction 90 there is provided a window lock so constructed that it may be positioned on the window sash and engage the window frame so that in moving the sash either up or down the lock operates eccentrically so that the further the sash is moved the tighter the lock engages the window frame, thus preventing the movement of the sash either up or down. That the lock may be readily secured to any window sash in the position desired to prevent movement of the sash up or down.

Having thus described my invention what I claim as new and desire to secure by Letters Patent, is:

1. In a window lock, a supporting member pivotally connected to the window sash, 110

another member pivotally connected to said supporting member adapted to fold against said supporting member and when folded forms an eccentric with the pivotal mounting of said supporting member.

2. In a device of the class described, a supporting member, a screw for securing one end of said supporting member to a window sash, another member pivoted on the opposite end of said supporting member adapted to fold against said supporting member and so formed that an eccentric is provided with the pivotal mounting of said support.
10. 3. In a device of the class described, a

supporting member, a screw for securing one end of said supporting member to a window sash, another member pivoted on the opposite end of said supporting member adapted to fold against said supporting member and so formed that an eccentric is provided with the pivotal mounting of said support and means secured to said pivotally mounted member adapted to engage the window frame when said pivotally mounted member is folded against said support.

In testimony whereof, I have hereunto set my hand at San Diego, California, this 7th day of May, 1919.

OSCAR L. DANFORTH.
